[57] CLAIM

The ornamental design for an air guide element for vehicle, as shown and described.

DESCRIPTION

FIG. 1 is a front view of a first embodiment of an air guide element for vehicle according to my novel design;

FIG. 2 is a top view of the first embodiment of the air guide element for vehicle according to my novel design;

FIG. 3 is a bottom view of the first embodiment of the air guide element for vehicle according to my novel design;

FIG. 4 is a right side view of the first embodiment of the air guide element for vehicle according to my novel design;

FIG. 5 is a left side view of the first embodiment of the air guide element for vehicle according to my novel design;

FIG. 6 is a perspective view from the top right of the first embodiment of the air guide element for vehicle according to my novel design;

FIG. 7 is a front view of a second embodiment of an air guide element for vehicle according to my novel design;

FIG. 8 is a top view of the second embodiment of the air guide element for vehicle according to my novel design;

FIG. 9 is a bottom view of the second embodiment of the air guide element for vehicle according to my novel design;

FIG. 10 is a right side view of the second embodiment of the air guide element for vehicle according to my novel design;

FIG. 11 is a left side view of the second embodiment of the air guide element for vehicle according to my novel design; and,

FIG. 12 is a perspective view from the top right of the second embodiment of the air guide element for vehicle according to my novel design/

The dash line included depicts environment and is not part of the claimed design.
